(57) **CLAIM**

The ornamental design for a sleeve with side tabs, as shown and described.

DESCRIPTION

FIG. 1 is an elevated perspective view of the sleeve with side tabs, showing my design;

FIG. 2 is a front view of the sleeve with side tabs;

FIG. 3 is an opposing rear side view of the sleeve with side tabs;

FIG. 4 is a left side view of the sleeve with side tabs;

FIG. 5 is an opposing right side view of the sleeve with side tabs;

FIG. 6 is a top view of the sleeve with side tabs;

FIG. 7 is an opposing bottom view of the sleeve with side tabs; and,

FIG. 8 is another elevated perspective view of the sleeve with side tabs.

In FIG. 8, the features of the bottle shown in phantom lines are for illustrative purposes only and do not constitute a part of the claimed design.
